UNITED STATES PATENT OFFICE.

PETER H. HERMSEN, OF LITTLE CHUTE, WISCONSIN.

DESIGN FOR A PNEUMATIC-TIRE SHOE.

Application filed March 22, 1924. Serial No. 9,045. Term of patent 7 years.

To all whom it may concern:

Be it known that I, PETER H. HERMSEN, a citizen of the United States, residing at Little Chute, in the county of Outagamie and State of Wisconsin, have invented a new, original, and ornamental Design for Pneumatic-Tire Shoes, of which the following is a specification, reference being had to the accompanying drawing, forming part thereof.

Figure 1 is a fragmentary top plan view of a pneumatic tire shoe, showing my new design, and

Figure 2 is a detail fragmentary transverse sectional view thereof.

I claim:

The ornamental design for a pneumatic tire shoe as shown.

P. H. HERMSEN.
